FIG. 5.

Inventor:

Edward R. Brainerd.
By Hazard & Miller Atty's.

UNITED STATES PATENT OFFICE.

EDWARD R. BRAINERD, OF LOS ANGELES, CALIFORNIA.

DAVENPORT.

Application filed December 29, 1921. Serial No. 525,621.

To all whom it may concern:

Be it known that I, EDWARD R. BRAINERD, a citizen of the United States, residing at Los Angeles, in the county of Los Angeles and State of California, have invented new and useful Improvements in Davenports, of which the following is a specification.

My invention relates generally to furniture, and more particularly to a davenport or divan, the principal object of my invention being to provide an article of furniture of the type referred to having a movable seat frame that is constructed so that it may be reversed in position, thereby serving as a seat cushion and as a box mattress for a pad and bedding, said movable seat frame being mounted in the frame of the davenport or divan so that it may be readily manipulated when shifted from one position to the other.

Further objects of my invention are to provide a davenport or divan having a reversible seat portion; to provide rolling supports for said seat portion, which rolling supports are contained within the hollow ends of the davenport or divan; to provide simple and efficient means for supporting the movable frame while the same is positioned to form a seat or a bed bottom; to provide means for securing the movable portion of the davenport against displacement when serving as a seat or bed bottom; to provide a construction that will permit of the ready formation of a bed bottom that corresponds in width to the width of an ordinary three quarters bed or double width bed; and, further, to generally improve upon and simplify the construction of the existing types of convertible davenports and couches and at the same time to provide

a construction that requires little effort on the part of the operator in shifting the movable frame from one position to the other when converting the davenport into a bed and vice versa.

With the foregoing and other objects in view, my invention consists in the features of construction and combination and ar-

rangement of parts hereinafter more fully described and claimed, reference being had to the accompanying drawings, in which

50

Figure 1 is a perspective view of a davenport constructed in accordance with the principles of my invention;

Figure 2 is an enlarged vertical section taken on the line 2—2 of Figure 1;

55

Figure 3 is an enlarged cross section taken on the line 3—3 of Figure 1;

Figure 4 is a horizontal section taken on the line 4—4 of Figure 2;

60

Figure 5 is a section showing a modified arrangement of the support for the movable seat portion of the davenport;

Figure 6 is a vertical section of a modified construction that permits of the formation of a double width or three quarters bed;

65

Figure 7 is a detail section of a rail that is arranged on the front of the movable seat frame;

Figure 8 is a fragmentary section of a modified form of the support for the reversible seat frame of my improved davenport.

Referring by numerals to the accompanying drawings, which illustrate a practical embodiment of my invention, 10 designates the back wall or panel of the body of the davenport or divan, and 11 the ends thereof, said ends being of any desired form and finish, and their lower front corners being connected by a longitudinally disposed rail

75

12. The ends 11 are composed of outer walls or panels 13 and inner walls or panels 14, said walls or panels being spaced apart a slight distance, and secured to the inner faces of the outer walls 13 a short distance above the lower ends thereof are horizontally disposed rails 15 that serve as tracks for rolling supports that are arranged on the ends of the movable seat frame of the davenport. Formed in the inner panels 14 and preferably immediately above the rails 15 are horizontally disposed slots 16 which are for the accommodation of the axles or

5 pinterles that carry the rolling supports for the movable seat frame. Secured in any suitable manner to the inner face of the rear wall or panel 10 that forms the back of the body of the davenport is a longitudinally disposed rail 17 that serves as a support for the rear portion of the movable seat frame.

10 Connected by suitable hinges 18 to the upper edge of front lower rail 12 so as to swing outwardly and downwardly is a longitudinally disposed panel 19 and secured by hinges 20 to the upper edge of said panel so as to swing inwardly and downwardly is a panel 21 from the upper edge of which 15 projects upwardly one or more dowel pins, such as 22. Seated in the panel 19 and preferably at a point midway between its ends is a suitable latch 23 having a portion that is adapted to engage in the under edge of 20 panel 21 when the latter occupies a vertical position above the panel 19, as illustrated in Figure 3, said latch being provided on its outer end with a button, knob or ring, such as 24, which latter may be engaged to operate the latch and to move the panels 19 and 21 into and out of seat frame supporting position.

30 The movable seat frame of my improved davenport or divan comprises a substantially rectangular frame that includes a front rail 25, a rear rail 26, and end rails 27. The length of this frame is slightly less than the distance between the inner panels 14 of the ends 11 of the davenport, and 35 one side of said frame may be cushioned and upholstered, as designated by 28, to form a cushioned davenport seat, while the other side may be upholstered or covered with suitable fabric, such as 29, to form a 40 surface adapted to receive bedding. Coil springs 30 are arranged between the bed surface 29 and the cushioned seat 28, thereby providing resiliency for both sides of the movable seat frame.

45 The front face of the back wall or panel 10 above the rail 17 is preferably upholstered and covered with a section 31 of suitable material, such as leather or fabric. Secured to the lower front face of the front rail 25 of the movable seat frame is a relatively narrow longitudinally disposed rail 32, the under side of which is recessed in order to receive the dowel pins 22 and secured to the upper portion of the outer face of 50 rear rail 26 is a relatively narrow strip or rail 33 having recesses in its upper surface that are adapted to receive the dowel pins 22 when the seat frame is inverted to form a bed bottom.

60 Under normal conditions or while the article of furniture is in service as a davenport or divan, rail 32 bears directly on top of rail 21 and rail 33 bears directly on top of rail 17, and with the parts thus positioned 65 the rollers 34 that serve as rolling supports

for the seat frame are elevated slightly with respect to the top surfaces of the rails 15, as illustrated in Figure 2. These rollers 34 are journaled upon axles or spindles 36 that are seated in the end rails 27 of the movable seat frame, said axles or spindles passing through the slots 16 in the end frames of the davenport, and said rollers 34 occupying the spaces between the panels 13 and 14. 75

Thus, while the movable frame is in service as a seat or a bed bottom, the rails 32 and 33 serve to support the frame, thereby taking the load off the rollers 34, but when the movable frame is drawn forwardly in order that it may be turned over, the rollers 34 ride directly upon the rails 15, thereby enabling the frame to be readily drawn forward or to a position where it may be turned over. Obviously, in order to permit the seat frame to be turned over, the front panels 19 and 21 must be swung outwardly and downwardly, which movement is effected by releasing the latching device 23 and pulling outwardly upon the ring or knob 24; when such operation is effected panel 19 swings outwardly and downwardly upon its hinges 18, and panel 21 swings inwardly relative to the upper edge of panel 19, as shown by dotted lines in Figure 3. 95 When the panels are thus drawn forwardly and downwardly, the under side of the ledge or rail 32, which is grooved lengthwise at two places to form a pair of finger recesses 32a, as illustrated in Figure 7, is engaged and the movable frame is drawn forwardly a sufficient distance from the rail 33 to clear rail 17, and with the rollers 34 serving as axes the seat frame may be readily turned over so that the upholstered surface of the seat is positioned on the under side of the frame and, after such operation, the frame is returned to its normal elevation with rail 32 bearing on rail 17 and with rail 33 bearing on rail 21. As the panels 19 and 21 are returned to their normal vertical positions, the front portion of the seat member will be elevated slightly by the knee joint leverage between the panels 19 and 21, thereby lifting the rollers 34 off the rails 15, and as the dowel pins 22 are positioned in the recesses in rail 32 the movable frame will be very firmly retained in proper position for use. It will be noted that rail 32 serves a three-fold purpose, 100 namely, it provides a bearing for the front side of the seat frame upon the hinged panel 21; second, it serves as a handle to be manually engaged when the seat frame is drawn forwardly and turned upside-down; and, 105 third, the recesses in its under side are engaged by the dowel pins 22 to firmly secure the seat frame in normal position.

When the seat frame is inverted to position the covering 29 uppermost, suitable 110

bedding may be positioned on the frame, thereby providing a single width bed.

The operations just described are practically repeated when the seat frame is turned 5 over so as to position the upholstered surface of said frame uppermost, and when so positioned the structure serves as a davenport or divan.

In Figure 5 I have shown a modified 10 structure wherein the reversible seat frame is suspended from rods or rails, such as 36, by means of hangers 37, which latter are provided at their upper ends with rollers 38 that ride freely upon said rails 36.

15 The construction illustrated in Figure 3 is utilized where the seat frame is of the usual single width, but when it is desired to provide a bed bottom of the usual three quarters width the movable seat frame is 20 made relatively wider than a single width frame, as illustrated in Figure 6, and the rollers 34^a are arranged off center or at points closer to the rear rail than the front rail of the frame.

25 This arrangement of the rollers permits the seat frame to be turned upside-down, for the distance from the rollers to the rear edge of said frame is less than the distance from the axes of the rollers to the floor. In 30 this connection, it will be understood that if the rollers were placed at points midway between the front and rear edges of the folding frame it would not be possible to invert said frame in the desired manner.

35 When it is desired to provide a bed bottom of full or double width, a cushioned and upholstered section, such as 39, is removably arranged on the inner face of the back panel 10^a immediately above the plane normally occupied by the seat frame. To form 40 the double width bed, the movable seat frame of three quarters width is drawn forwardly and the section 39 is shifted downwardly into a substantially horizontal plane 45 to the rear of the movable seat frame, thereby combining with said seat frame in forming a bed bottom of the usual double width.

In Figure 8, I have illustrated a swinging support for the movable seat, which support takes the form of a substantially Z-shaped arm 40, the upper horizontally disposed portion of which is journaled in the end of the davenport and the lower horizontally disposed portion is journaled in the end rail of the seat frame. Such construction 55 permits the seat frame to be rocked forwardly a sufficient distance to permit it to be turned upside-down when converting the davenport into a bed or vice versa.

60 A davenport of my improved construction is comparatively simple, may be easily and cheaply produced, is capable of being readily manipulated when converted from a davenport into a bed and vice versa, provides in a single piece of furniture a struc-

ture that may serve as a davenport or divan and which may be readily converted into a bed of single, three quarters or double width, and the mounting of the movable seat frame upon rolling supports eliminates 70 all links, levers, hinges and like connections between said frame and the frame of the davenport or divan.

It will be understood that minor changes 75 in the size, form and construction of the various parts of my improved davenport or divan may be made and substituted for those herein shown and described without departing from the spirit of my invention, the scope of which is set forth in the appended 80 claims.

I claim as my invention:

1. In a davenport, a frame including end supports and a pair of panels hinged to each other to form a knee joint, and a reversible 85 seat frame supported on the end supports to be engaged by the panels when the latter are in extended position for supporting the frame independently of the end supports.

2. A davenport having substantially hollow ends, supporting rails arranged within 90 said hollow ends, a reversible seat frame arranged between said hollow ends, and rollers on the ends of said seat frame, which rollers bear on said rails within said hollow ends. 95

3. In a davenport, a frame, ledges on the 100 ends thereof, a movable seat frame, rollers on the ends thereof, which rollers are adapted to bear on said ledges, and hinged panels providing a support for the front of said seat frame and adapted to normally maintain the same in position with the rollers elevated from said ledges.

4. In a davenport, a frame, roller supporting rails sustained on the ends of the frame, a reversible seat frame, rollers carried by the seat frame and adapted to engage 105 said rails, a supporting rail secured to the back of the first frame, and a front panel hingedly secured to the first frame and composed of sections hinged to occupy an extended position in which they cooperate with the supporting rail for supporting the seat frame in such a position that the rollers are out of contact with said rails, and a folded position in which the rollers engage the rails to allow of the sliding of the seat frame to disengage the supporting rail and thereby allow rotation of the seat frame. 110

5. In a davenport, a frame, roller supporting rails sustained on the ends of the frame, a reversible seat frame, rollers carried by the seat frame and adapted to engage said rails, a supporting rail secured to the back of the first frame, sustaining rails secured to the seat frame and having dowel receiving recesses formed therein, a front panel hingedly secured to the first frame and composed of sections, rotatable means for locking the sections in expanded position, and 125 130

dowel pins carried by one of the sections and adapted to engage within the openings of said rails for the purpose described.

6. In combination, a davenport frame, 5 roller supporting rails at the ends of the frame, a reversible seat frame, rollers carried by the seat frame and adapted to engage said rails, whereby sliding movement or rotation of the seat frame is permitted, 10 and foldable means associated with the dav-

enport frame to engage when in extended position the seat frame to maintain the latter against sliding and rotational movements and to support the frame in elevated position wherein the rollers are out of contact with the rails. 15

In testimony whereof I have signed my name to this specification.

EDWARD R. BRAINERD.
